Inventor:

George Thompson
by Joel C.R. Palmer Atty

UNITED STATES PATENT OFFICE.

GEORGE THOMPSON, OF MOUNT VERNON, NEW YORK, ASSIGNOR TO WESTERN ELECTRIC COMPANY, INCORPORATED, OF NEW YORK, N. Y., A CORPORATION OF NEW YORK.

IMPULSE SENDER.

Application filed November 3, 1919. Serial No. 335,289.

To all whom it may concern:

Be it known that I, GEORGE THOMPSON, a citizen of the United States, residing at Mount Vernon, in the county of Westchester 5 and State of New York, have invented certain new and useful Improvements in Impulse Senders, of which the following is a full, clear, concise, and exact description.

This invention relates to an impulse-sending device which is adapted to be used in connection with telephone exchange systems where it is desired to differentiate between the parties making a call.

The principal object of the invention is 15 the provision of means, beyond the control of the calling subscriber, for transmitting a definite series of impulses over the line.

In accordance with a feature of the invention, said means is provided in conjunction 20 with the switchhook of the subscriber's set and is put into an operative condition upon the removal of the receiver from the switchhook.

It is thought that a more definite understanding 25 of the invention may be had from the following description taken in conjunction with the accompanying drawing in which Fig. 1 shows a telephone line having a plurality of stations connected therewith 30 where a telephone set is located, in which there is provided means whereby it is possible to differentiate between the various parties located on the line. In Fig. 2 there is shown a sectional view taken across the 35 line 2—2.

In the drawing in which the same reference characters represent like parts, 4 represents a telephone set which is provided with the usual transmitter 5 and receiver 6, the 40 receiver 6 being adapted to be supported pendently by means of a switchhook 7. The switchhook 7 is L-shaped and has a portion thereof, as designated by the numeral 8, which maintains contact spring 9 out of engagement with contact springs 10 and 11 as 45 long as the receiver is on the switchhook. The closure of contact springs 10 and 11, upon the release of contact spring 9, connects the telephone set with the telephone line C. These contact springs, together with the normally engaged contact springs 12 and 50 13, are secured to a member 14 by means of bolts 15 and 16. The various contact springs are insulated from one another by means of 55 an insulating material 17. The member 14

extends up through the post portion 4 of the standard and is suitably secured to the basic member thereof.

A ratchet wheel 18, together with an impulse wheel 19 having a series of cam teeth, 60 is secured to the portion of the switchhook that is mounted within the casing 4 by means of a suitable rivet 20. The impulse wheel 19 is so attached to the ratchet wheel 18 that any movement thereof will cause a 65 similar movement of the impulse wheel. The number and arrangement of the teeth on the impulse wheel will be in accordance with the designation of the station at which it is to be used. The ratchet wheel 18 is arranged with an operating pawl 21 for engaging 70 the teeth thereof. The pawl 21 is secured to the switchhook 7, whereby when the switchhook is caused to assume a position other than its normal position, the 75 ratchet wheel 18 will be caused to advance a step.

The contact spring 13, which is normally in engagement with contact spring 12, has its upper portion so arranged as to engage 80 the teeth of the impulse wheel 19. It is thus seen that when the ratchet wheel 18 is caused to be revolved by an upward movement of the switchhook 7 for causing a similar movement of the impulse wheel 19, that the contact spring 13 will be caused to ride over the teeth of the impulse wheel. The number of times that the contact between the contact springs 12 and 13 is made and broken, will, 85 of course, depend upon the number of teeth 90 over which the contact spring 13 is caused to ride.

The number of teeth which the impulse wheel must necessarily be provided with will depend upon the number of parties 95 connected with the telephone line, referring, of course, to a party line to which the invention is especially applicable. If the device is applied to a party line, the set supplied to party I would not be equipped with 100 an impulse wheel as the single impulse necessary for conditioning the energizing circuit of the operating magnet I will be transmitted upon the removal of the receiver from the switchhook. However, for the 105 other parties on the line different impulse wheels must be provided having 1, 2 and 3 teeth respectively, for each tooth on the ratchet wheel 18, so as to transmit 1, 2 and 3 impulses respectively, at each actuation of 110

2

the switchhook. It is obvious that this arrangement is capable of being applied to a telephone line having any number of subscriber sets connected therewith.

5 The operation of a device of the character as applied to an automatic telephone exchange system, is as follows: Let us assume that party W, which is the fourth party on the line, desires to initiate a call, in which 10 case the impulse wheel 19 will have four teeth to each tooth of the ratchet wheel 18. The subscriber, in removing his receiver from the switchhook in the usual manner, causes ratchet wheel 18 to be moved from its 15 position of rest and stepped around one step, so that the following tooth will be engaged by the pawl 21. The removal of the receiver from the switchhook also causes the release of contact spring 9 for actuating contact springs 10 and 11, thereby connecting 20 the set with the line 11. The movement of the ratchet wheel 18 in this manner, thereby causes a similar movement of the impulse wheel 19 which causes the disengagement of 25 the contact springs 12 and 13 and the consequent sending of the preliminary impulses. The transmission of these impulses thereby causes the operation of relay 22, the energizing circuit of which extends from battery 30 through the left-hand winding of relay 22, left-hand normal contact of cut-off relay 23, contacts of sender 36 (not shown) closed contacts of contact springs 13, 12, 9, 10 and 11, conductor 24, right-hand normal contact 35 of cut-off relay 23 and the right-hand winding of relay 22 to ground. Relay 22, on being energized, attracts its armature 25, moving a stepping pawl 26. The stepping pawl 26 thereby moves the ratchet wheel 27, 40 carrying an arm 28, into engagement with contact 29 which is associated with the operating magnet I for preparing an operating circuit for the message register individual to the subscriber. The ratchet wheel 27 is 45 held in its actuated position by means of a holding pawl 35. Contacts 30, 31 and 32 are contacts associated with the operating magnets II, III and IV, and the registers individual thereto. The operating magnets 50 control the registers by attracting an armature 33 carrying a stepping pawl which steps the register wheel 34 one step for each energization of the operating magnet.

There are also three other preliminary 55 impulses or interruptions of the energizing circuit of relay 22, produced by the breaking of the circuit through contacts 12 and 13 by the impulse wheel 19. The arm 28 is thereby moved from one contact to the other until 60 it reaches contact 32 where it is brought to rest due to the energization of relay 22 which now pulls up its armature for a longer period of time in which the energization of relay 22 establishes, at its left-hand contact, a circuit for causing the operation of

slow to operate relay 40. Upon the operation of slow to operate relay 40, the energizing circuit of the electromagnet controlling the operation of a selector (not shown) for selecting an idle trunk is completed 70 through the alternate contacts of this relay. Relay 40 is of the slow to operate type since it is not desired to operate the selector switch on the momentary operation of relay 22 for advancing the element 28 into engagement with the desired one of the contacts associated with the message register. The selector switch seizing an idle trunk, thereby causes the energization of cut-off relay 23, which disconnects relay 22 from 80 the line conductors for causing the deenergization thereof. The subscriber can, at this time, operate his sender 36 for causing the operation of the apparatus of the central office for connecting his line with the line 85 of the called-for party. The called-for party, in answering the call by removing the receiver from the switchhook, sets up a condition on conductor 37 which causes the energization of operating magnet IV for actuating the message register. The energizing circuit thereof may be traced from battery through the winding of magnet 4, contact 32, arm 28 and conductor 37 to ground at the central office (not shown). 90

On the release of the selector switch at the central office, cut-off relay 23 is de-energized and thereby withdraws the holding pawl 35 from engagement with the ratchet wheel 27, whereupon arm 28 returns 100 to normal.

The invention, as described herein, has been applied to an automatic telephone system but it is obvious that it may be employed in systems of other types in which 105 it is desired to differentiate between the various parties of a party line for operating the message registers individual to each one of the parties on that line.

What is claimed is:

1. The combination with a telephone set of a switchhook, a ratchet wheel associated with and directly under the control of said switchhook, an impulse wheel operated by said ratchet wheel due to an upward movement of said switchhook, and contact springs actuated by said impulse wheel for sending preliminary impulses.

2. The combination with a telephone set of means for automatically sending preliminary impulses, said means comprising an interrupter, a switchhook, and a ratchet wheel controlled solely by said switchhook to operate the interrupter.

3. The combination with a telephone set of means for automatically sending preliminary impulses, said means comprising a switchhook, contact springs, an impulse wheel arranged in close proximity to said contact springs, and means controlled sole- 130

ly by said switchhook for causing the rotation of said impulse wheel, and in consequence thereof, the actuation of said contact springs.

5. 4. The combination with a telephone set of means for automatically sending preliminary impulses, said means comprising a switchhook, contact springs, an impulse wheel arranged in close proximity to said contact springs, an operating pawl secured to said switchhook, and means operated by said pawl due to an upward movement of said switchhook for causing the rotation of said impulse wheel, and in consequence thereof, the actuation of said contact

5. The combination with a telephone set of an interrupter mechanism arranged in conjunction with the switchhook for automatically sending preliminary impulses, said 20 interrupter mechanism comprising contact springs, an impulse wheel mounted in close proximity to said contact springs, and means controlled entirely by the switchhook for causing the rotation of said impulse wheel, 25 and in consequence thereof the actuation of said contact springs.

In witness whereof, I hereunto subscribe my name this 31st day of October, A. D., 1919.

GEORGE THOMPSON.
